W. E. WHITE,
BAR SPACING DEVICE,
APPLICATION FILED APR. 12, 1920.

Patented July 11, 1922.

Inventor
William E. White
By *Thomas L. Wilson*
Atty.

UNITED STATES PATENT OFFICE.

WILLIAM E. WHITE, OF CHICAGO, ILLINOIS.

BAR-SPACING DEVICE.

1,422,157.

Specification of Letters Patent. Patented July 11, 1922.

Application filed April 12, 1920. Serial No. 373,339.

To all whom it may concern:

Be it known that I, WILLIAM E. WHITE, a citizen of the United States, and resident of Chicago, in the county of Cook and State 5 of Illinois, have invented certain new and useful Improvements in a Bar-Spacing Device, of which the following is a specification.

My invention relates to the art of concrete reinforcement and particularly to an 10 improvement on the construction shown in my co-pending application Serial No. 370,453, filed April 1, 1920.

An object in the construction of the device here illustrated is to provide a simple 15 and economical spacing element adapted to be constructed from wire, the separate parts being welded in order to join the same.

The idea sought to be protected herein is, 20 like that of the construction shown in my companion application, heretofore referred to, that of utilizing a single continuous length of wire or wire rod, and securing chairs or supports thereto at intervals by 25 welding. The chairs are also composed of wire bent into generally V-shape, the V being inverted when the device is in operative position. A distinction in this construction over that shown in the application referred 30 to is in that the longitudinal wire is positively supported and the weight thereof, together with the weight of the bar supported thereby, is not dependent upon the strength 35 of the weld.

The invention will be more readily understood by reference to the accompanying drawing wherein:

Fig. 1 is a plan view of a section of a 40 spacing device constructed in accordance with my invention;

Fig. 2 is a side view;

Fig. 3 is an end view thereof;

Fig. 4 is a perspective view of a modified form;

Fig. 5 is an end view thereof; and

Fig. 6 is a side elevation of said modified form.

In the drawings, and referring to the construction shown in Figs. 1 to 3, it will be 50 seen that I provide a continuous length of wire 10 which may be of suitable strength and stiffness to meet the requirements of specific cases. At intervals in the length of wire I provide chairs, the spacing being 55 determined by the spacing of the reinforcing bars to be supported thereby. These

chairs comprise two oppositely diagonally projecting legs 11, 12, joined by an intermediate angularly disposed member 13, the wire being bent in such manner that the connecting wire 13 is located beneath the strand 10, of wire, whereas the bends 14 at the upper ends of the legs overlie the strand, the connecting wire 13 being welded to the strand 10 at their intersection. A chair is 60 formed which, in plan view, outlines a Z, the connecting member extending crosswise of the strand. In this construction the weight of the strand and a bar which may be mounted on the strand or between the legs is 65 directly carried by the cross member 13.

As a means for securing a reinforcing bar in position I may provide a short length of annealed wire 15, and an intermediate point 16 of which is shaped to conform to the connecting member 13 and is welded to the lower edge thereof. The terminal portions 75 of the wire 15 will lie on opposite sides of the strand and may easily be bent upward and twisted around a reinforcing bar. 80

In the construction shown in Figs. 4, 5 and 6 the strand 17 is the same as that described the chair being similar to that shown in my application heretofore referred to in that it is composed of a section of wire 85 bent to form a loop, the loop being bent transversely to form legs 18, 18, and 19, 19, the latter legs being joined by a cross member 20. The distinction over the construction of my prior application is in that I 90 provide a seat or pocket 21 at the bend in the loop, the seat accommodating the strand 17 which is welded thereto. Thus the weight of the supported parts is carried directly instead of through the medium of 95 the weld as in the preceding case. In this construction the sharp bends 22, at the upper ends of the legs, may project considerably above the upper edge of the strand wire, thus forming a more distinctly outlined pocket for the reception of the reinforcing rod. 100

A tie wire, such as indicated at 23, is secured by welding to the chair and may be bent around the reinforcing rod holding 105 the same in position. Obviously other modifications than those here shown may be made without departure from the spirit of my invention.

I claim:

1. A spacing device, comprising in combination a continuous length of wire, and

110

spaced chairs welded to the wire at intervals, said chairs being composed of a length of wire bent into inverted V-shape and provided with a pocket at the apex of the V, said pocket being located beneath said length of wire and serving to support the wire independently of the weld, substantially as described.

2. In a bar spacer, the combination of a single continuous length of wire, and wire chairs welded thereto at intervals, said chairs being composed of a portion lying alongside of said length of wire and beneath the same, and two legs joined to said portion and one thereof bent over the wire, substantially as described.

3. In a bar spacer, the combination of a single continuous length of wire and chairs composed of two oppositely diagonally projecting legs, and a horizontal member integral with the legs, said member lying beneath the wire and said legs being bent over the wire, substantially as described.

4. A spacing device comprising in com-

bination a continuous length of wire, and supporting chairs also composed of wire and bent to provide a pair of oppositely projecting diagonal legs arranged in planes transverse to said length of wire, said legs being spaced apart longitudinally of the length of wire and joined by a horizontal member, the length of wire extending over said horizontal part and beneath the upper ends of said legs.

5. In a spacing device, the combination of a continuous length of wire, and chairs also composed of wire and bent to provide a V-shaped structure as viewed from a point at an end of said length of wire, the length of wire co-operating with the chair at the apex of the V and being welded thereto, a portion of said chair being bent over and another portion lying under said length of wire.

Signed at Chicago, Illinois, this 9th day of April, 1920.

WILLIAM E. WHITE.
